John H. Campfield,
ATTORNEY.

UNITED STATES PATENT OFFICE.

WILLIAM M. STIDWORTHY, OF HACKETTSTOWN, NEW JERSEY.

DEVICE FOR FORMING EYES IN METAL STRIPS.

1,387,020.

Specification of Letters Patent.

Patented Aug. 9, 1921.

Application filed June 8, 1920. Serial No. 387,418.

To all whom it may concern:

Be it known that I, WILLIAM M. STIDWORTHY, a citizen of the United States, and a resident of Hackettstown, county of Warren, 5 and State of New Jersey, have invented certain new and useful Improvements in Devices for Forming Eyes in Metal Strips, of which the following is a specification.

This invention relates to an improved device for bending the ends of metal strips to form eyes, and is illustrated and described as a machine for forming eyes in the ends of spring leaves, this being the use for which the invention is primarily intended. 10 The invention consists of a device that is economically made and is efficient in its operation and is also portable, being usually operated after it is secured in a vise or any other ordinary shop fixture by means of 15 which it can be securely held, thus making it unnecessary to establish in a shop a special base or machine for this purpose.

The invention is further designed to provide a device of this kind which is easily adjusted to take in different widths and thicknesses of metal strips, the adjustment being quickly accomplished. The device is so constructed that when the dog which grasps the end of the strip is swung concentrically 20 around a roller or other suitable annular element, the metal is carried along with it and does not retreat at the start of the rotative movement, which is the difficulty in some types of machines for carrying out the operation of forming eyes in springs and the like.

The invention is illustrated in the accompanying drawing, in which Figure 1 is a top view of the device with the handle broken away. Fig. 2 is a side view of the device shown in Fig. 1, and Fig. 3 is a detail section on line 3—3 in Fig. 1, but with the swinging element lowered to approximately the position it assumes at the beginning of the bending operation.

The device comprises a suitable support 10 which is usually made substantially flat on the top, so that the metal strip 11, such as a spring leaf or similar strip, can be supported, and in order to guide and approximately position the strip in the center of the support I arrange a suitable gage 12, which is transversely adjustable, the adjustment in the form shown being provided by mounting 50 the gage on a stud 13, on which it is held in

its different adjusted positions by a set-screw 14.

The rear end of the support is preferably provided with a means for securing it in a vise or similar clamping means; Fig. 2 illustrating, in dotted outline, the jaws 15 of a vise which securely hold the post 16, which is the means by which the support is held in position.

On the forward end of the support is the 65 bending mechanism which comprises a fixed rotative element and also a swinging element, the rotative element comprising a roller 17 which is mounted on the end of the support and is spaced therefrom by means of the bearing blocks 18 and the pintle or pivotal pin 19. The pintle 19 is readily removable, fitting loosely in perforations in the bearing blocks and also fitting loosely in the perforation through the roller 17, so that a 70 different size roller can easily be installed.

The bearing blocks 18 are adjustable relative to the support to bring about the spaced relation heretofore mentioned, the form 75 shown comprising the screw-threaded shanks 20 which fit in screw-threaded holes in the support, and it will be readily understood that when they are turned they are raised or lowered, and after the pivotal pin is inserted they are prevented from rotating and thus 80 not only act as a support for the roller, but also as a means of adjustment.

The swinging element is arranged so that it can be swung concentrically relative to the roller, the preferred form being a yoke 21, 85 the ends of which are perforated to receive the pivotal pin 19 so that the yoke also is supported by the pivotal pin and is freely rotatable thereon. The yoke 21 is provided with a handle 22, usually two or three feet long to 90 give the required leverage, this handle being adjustable longitudinally in the yoke, this longitudinal adjustment being preferably provided by placing a screw-thread 23 which operates in a fixed screw-threaded bearing 95 block 24.

The inner faces of the arms of the yoke are provided with the grooves 25 in which slides a block 26, this block being attached to the end of the screw and being moved forward and backward with it. The block 26 has a cam 27 mounted therein, usually on a pin 28, the cam having a handle 29 by means of which the cam can be swung.

Freely slidable above the cam is the dog 110

30, which is provided with a gripping face, and I have found a positive grip secured by tapering the faces 31 to make the upper or forward end of the dog pointed, and by milling out or otherwise establishing the groove 32, parallel knife edges or ridges 33 are provided which, when forced against the end of the strip 11, tightly bind it and there is no slipping of the dog on the strip.

10 After the roller 17 is installed at its properly adjusted position, the strip 11 is placed on the support 10 the yoke being in the position shown in Fig. 3, with the handle 29 swung upward so that the dog 30 does not interfere with the insertion of the strip. The handle 29 is then swung in the direction of the handle 22 so as to bring the two handles conveniently together, this forcing the dog 15 tightly against the end of the strip 11. The yoke is then swung by means of the handle 29 in conjunction with the handle 22, and as it is swung, as shown in Fig. 2, it carries with it the end of the strip which, on the 20 continued swinging of the yoke, is formed into an eye. Usually one movement of the yoke to its limit of movement is sufficient for forming a complete eye, but if further twisting is desired the handle 29 can be 25 swung to release the block and the yoke swung out of engagement with the strip, and at a suitable point, by again swinging the handle 29 toward the handle 22, the dog once more engages the strip and a further forcing 30 of the end of the strip to form a more complete eye can be accomplished.

35 When the eye has been formed the pivotal pin 19 is withdrawn and the roller removed. If the roller is a bushing to be used 40 within the eye it is, of course, left in place, but if the eye is to be used without a bushing the roller 17 is driven out and the operation is now complete.

45 It will be evident that slight changes in the form and assembling of the parts can be made without departing from the scope of my invention.

I claim:

50 1. A device for bending the ends of metal strips to form eyes comprising a support, a roller, means for mounting the roller so that it is adjustable relative to the support, a yoke swinging concentrically relative to the roller, a handle on the yoke, a bearing block adjustable in the yoke, a cam pivoted in the bearing block, a handle on the cam, and a dog 55 slideable in the yoke and against which the cam operates.

60 2. A device for bending the ends of metal strips to form eyes comprising a support, a roller, means for mounting the roller so that it is adjustable relative to the support, a yoke adapted to swing around said roller, a block, primary adjusting means for fixing 65 the position of the block on the yoke, a dog

slidable in said yoke, and means mounted on said block for forcing said dog toward the roller.

3. A device for bending the ends of metal strips to form eyes comprising a support, 70 bearing blocks on said support, the blocks and the support having co-acting means whereby the bearing blocks can be adjusted relative to the support, the bearing blocks having perforations therein, a roller having 75 a perforation therein, a readily removable pintle in the perforations of the bearing blocks and in the roller, means adapted to swing concentrically relative to said roller, said means including a dog, and means for 80 forcing said dog toward the roller.

4. A device for bending the ends of metal strips to form eyes comprising a support, bearing blocks on said support, the blocks and the support having co-acting means 85 whereby the bearing blocks can be adjusted relative to the support, the bearing blocks having perforations therein, a roller having a perforation therein, a readily removable pintle in the perforations of the bearing 90 blocks and in the roller, means adapted to swing concentrically relative to said roller, said means including a dog, a U-shaped yoke having its ends perforated, said perforations receiving the pivotal pin, a handle 95 arranged in extension of said yoke and in screw-threaded connection therewith, a block on the end of the handle, a cam swinging on the block and adapted to bear against the dog, and a handle on said cam and disposed so as to 100 be swung toward the first mentioned handle to force the dog toward the roller.

5. A device for bending the ends of metal strips to form eyes comprising a support, bearing blocks on said support, the blocks 105 and the support having co-acting means whereby the bearing blocks can be adjusted relative to the support, the bearing blocks having perforations therein, a roller having a perforation therein, a readily removable 110 pintle in the perforations of the bearing blocks and in the roller, means adapted to swing concentrically relative to said roller, said means including a dog, a U-shaped yoke having its ends perforated, said perforations 115 receiving the pivotal pin, a handle arranged in extension of said yoke and in screw-threaded connection therewith, a block on the end of the handle, a cam swinging on the block and adapted to bear against the dog, a 120 handle on said cam and disposed so as to be swung toward the first mentioned handle to force the dog toward the roller, and a transversely adjustable gage on said support in rear of said roller.

In testimony that I claim the foregoing, I have hereto set my hand, this 4 day of June, 1920.

WILLIAM M. STIDWORTHY.
